(57) **CLAIM**

The ornamental design for a container cap, as shown and described.

DESCRIPTION

FIG. 1 is a front elevational view of an embodiment of the container cap of the present invention;

FIG. 2 is a side elevational view of the container cap of FIG. 1;

FIG. 3 is a top plan view of the container cap of FIG. 1; and, FIG. 4 is a perspective view of the container cap of FIG. 1. The broken lines in the drawings are for illustrative purposes only and form no part of the claimed design.
